UNITED STATES PATENT OFFICE

154,471

DESIGN FOR A COMBINED LAMP AND OZONE GENERATOR

Harry Ginsberg and Charles Ginsberg,
Kansas City, Mo.

Application January 2, 1948, Serial No. 143,516

Term of patent 3½ years

(Cl. D48—20)

To all whom it may concern:

Be it known that we, Harry Ginsberg and Charles Ginsberg, citizens of the United States, residing at Kansas City, in the county of Jackson and State of Missouri, have invented a new, original, and ornamental Design for Combined Lamp and Ozone Generator, of which the following is a specification, reference being had to the accompanying drawing, forming part thereof.

Fig. 1 is a perspective view of a combined lamp and ozone generator showing our new design.

Fig. 2 is a plan view of the lamp and ozone generator.

Fig. 3 is an end elevation of the lamp and ozone generator.

We claim:

The ornamental design for a combined lamp and ozone generator, as shown.

HARRY GINSBERG.
CHARLES GINSBERG.
